UNITED STATES PATENT OFFICE.

BEN KAECH, OF BROOKLYN, WISCONSIN.

MAIL-BAG-DELIVERY APPARATUS.

1,213,106.

Specification of Letters Patent.

Patented Jan. 16, 1917.

Application filed August 2, 1916. Serial No. 112,819.

To all whom it may concern:

Be it known that I, BEN KAECH, a citizen of the United States, residing at Brooklyn, in the county of Green and State of Wisconsin, have invented new and useful Improvements in Mail-Bag-Delivery Apparatus, of which the following is a specification.

This invention relates to improvements in mail bag delivery apparatus whereby mail bags may be delivered from a moving train to a station and from the station to the moving train simultaneously.

In carrying out the present invention, it is my purpose to provide mail bag delivery apparatus of the class described wherein the mail bag carriers on the train and at the station respectively will be locked in delivery position and automatically released as the train passes the station and delivered from the station to the train and from the train to the station without necessitating the stopping of the train.

It is also my purpose to improve and simplify the general construction of mail bag delivery apparatus of the class described and provide apparatus wherein the component parts will be so arranged and correlated as to reduce the possibility of derangement to a minimum and enable access to be had thereto for the purposes of cleaning and repairing.

With the above and other objects in view, the invention consists in the construction, combination and arrangement of parts hereinafter set forth in and falling within the scope of the claims.

In the accompanying drawings; Figure 1 is a top plan view showing the complementary devices carried by the train and at the station respectively. Fig. 2 is an end view of the same. Fig. 3 is a view in side elevation of one of the devices. Fig. 4 is a longitudinal sectional view therethrough showing the locking mechanism. Fig. 5 is a cross sectional view through the same. Fig. 6 is a longitudinal sectional view showing the parts in inactive position. Fig. 7 is an enlarged perspective view of the carrier.

Referring now to the drawings in detail, 1, 1 designate complementary devices of the apparatus arranged upon the train and at the station respectively. The train carried device comprises a base plate 2 suitably fastened to one side of the doorway of the car and having the outer face thereof provided

with outwardly extending segmental plates 3 spaced apart in parallelism and arranged one above the other. Pivoted between the plates 3 at the center of the latter is one end of an arm 4 capable of swinging movement to a position outwardly of the car at right angles thereto and to a position within the car. Formed in the plates 3 are alining holes 5, while formed in the arm 4 is a hole 6 adapted to aline interchangeably with the holes 3 to receive a pin 7 whereby the arm may be held in adjusted position. Fastened to the lower edge of the arm 4 at the upper end thereof is a block 8 preferably set into the arm and having the ends projecting beyond the respective sides of the arm and formed in the projecting ends of the block 8 are openings 9. Passed through the arm 4 and the block 8 is a vertical pivot bolt 10 and pivoted upon the lower end of the bolt 10 is a bar 11 capable of swinging movement relatively to the arm, and adapted, when the arm is in active position, that is, at right angles to the car, to be swung to a position at right angles to the arm and, when the arm is in inactive position, that is, within the car, to be swung to a position parallel with the arm. Fastened to the respective sides of the bar 11 at one side of the arm 4 are plates 12 depending from the bar 11 and pivoted between the plates 12 is a lever 13 depending from the bar 11 and having the upper end formed with a bill 14 engaging one extremity of a horizontal finger 15 pivoted between its ends between the plates 12. The other end of the finger 15 is adapted to engage a shoulder 16 formed on a locking disk 17 rotatably mounted between the plates 12, and this disk 17 is formed with a transverse groove 18 in the periphery thereof that alines with alining grooves 19 formed in the lower edges of the plates when the shoulder 16 on the disk is engaged by the adjacent end of the finger 15. Secured to the lower edge of the bar 11 at the side of the lever 13 opposite from the bill 14 is a stop block 20 designed to limit the movement of the lever in one direction; and bearing upon the lever is a spring 21 that acts to hold the lever in normal position, so that the finger 15 may lock the disk 17 against movement. The other end of the bar 11 is formed with an impact head 22, while mounted upon the upper edge of the lever between the impact head 22 and the arm is a notched bar 23.

24 designates a carrier ring that is adapted to be placed in the alining grooves 18 and 19 and held in such grooves by the disk 17 and the finger 15 and secured to 5 the ring at opposite sides of the portion disposed within the alining grooves are transverse holding fingers 25. 26 designates a mail bag carrier embodying a partially circular frame 27 including longitudinal side 10 bars 28 and curved cross bars 29 connected to the side bars 28, and a top bar 30 arranged above the side bars and at a point approximately centrally of the distance between the said side bars. This top bar 30 15 is connected to the side bars by means of straps 31 and curved arms 32 formed integral with the end cross bars 29. Secured to the top bar 30 at a point centrally thereof is a block 33 and through this block the ring 20 24 is passed.

Secured to the lower portion of the lever 13 is a flag 34.

The device arranged at the station is identical in construction to the device carried by 25 the train except that the arm 4 is spaced apart from the bar 11 in order that the car carried device may clear the station device.

In practice, when the car carried device and the station device are in delivery positions 30 and the car passes the station, the impact head on the bar 11 of the train strikes the flag 34 on the lever 13 of the station device, thereby tilting the finger 15 to release the disk 17 so that the ring 24 is released 35 and drops onto the notched bar 23 on the moving train, the holding finger 25 engaging the respective edges of the notched bar to prevent swaying of the ring and carrier. The same action takes place in the car carried device so that the ring and carrier on 40 the car are delivered at the station.

The bar 11 is formed with an opening 35 adapted to aline with either one of the openings 9 in the block 8, according to the position 45 of the bar, to receive a pin 36 whereby the bar may be held stationary upon the arm.

While I have herein shown and described the preferred form of my invention by way 50 of illustration, I wish it to be understood that I do not limit or confine myself to the precise details of construction herein described and delineated, as modification and variation may be made within the scope of 55 the claims and without departing from the spirit of the invention.

I claim:

1. In mail bag delivery apparatus, complementary devices carried by the train and

station respectively, each embodying an arm 60 mounted for swinging movement to active and inactive positions, a bar on the outer end of said arm capable of swinging movement to active and inactive position, a ring carried by said bar and detachable therefrom, lock mechanism holding said ring to 65 said bar, and means on each bar for releasing the lock mechanism on the other bar to release said ring whereby the ring connected to one bar may be delivered to the other 70 bar.

2. In mail bag delivery apparatus, complementary devices carried by the train and station respectively, each embodying an arm mounted for swinging movement to active 75 and inactive positions, a bar on the outer end of said arm capable of swinging movement to active and inactive position, a ring carried by said bar and detachable therefrom, lock mechanism holding said ring to 80 said bar, means on each bar for releasing the lock mechanism on the other bar to release said ring whereby the ring connected to one bar may be delivered to the other bar, and coöperating means on said ring and 85 bar for holding the delivery ring on the bar against swaying.

3. In mail bag delivery apparatus, companion devices carried by the train and at the station respectively, each device embodying 90 an arm, a bar on the outer end of said arm, a carrier ring suspended from said bar, means locking said carrier ring on said bar, a flag connected to said locking means; and an impact head on said bar, the impact head 95 on each bar being adapted to engage the flag on the other bar to relieve the said ring of the influence of said locking means whereby the ring on each bar may be delivered to the other bar. 100

4. In mail bag delivery apparatus, companion devices carried by the train and at the station respectively, each device embodying an arm, a bar on the outer end of said arm, a carrier ring suspended from said bar, 105 means locking said carrier ring on said bar, a flag connected to said locking means, an impact head on said bar, the impact head on each bar being adapted to engage the flag on the other bar to relieve the said ring of 110 the influence of said locking means whereby the ring on each bar may be delivered to the other bar, and coöperating means on each ring and bar to hold the delivered ring against swaying on the bar. 115

In testimony whereof I affix my signature.

BEN KAECH.
